UNITED STATES PATENT OFFICE

AKSEL SOLUM, OF LANCASTER, NEW YORK

LAMP MOUNTING FOR BOWLING ALLEYS

Application filed December 28, 1931. Serial No. 583,478.

This invention relates to improvements in lighting devices or lamp mountings designed particularly for use on bowling alleys.

One of its objects is to provide a novel 5 mounting for the pit and foul light of bowling alleys which can be readily shifted out of the way, without disturbing or doing injury to the electrical connections, when it is desired to clean or resurface the alleys.

10 Another object of the invention is the provision of a lamp mounting of this character, which is simple and inexpensive in construction, which may be readily installed, and which is so designed that one unit mounting 15 serves two adjoining alleys.

In the accompanying drawing:—Figure 1 is a cross section taken through a pair of alleys showing my improved lamp mounting applied thereto. Figure 2 is a side elevation 20 thereof, the sub-flooring and stringers of the alleys being shown in section. Figure 3 is an enlarged cross section taken substantially in the plane of line 3—3, Figure 2. Figure 4 is a fragmentary side elevation showing the 25 lamp-carrying frame or yoke in its inoperative position or one parallel to the alleys.

Similar characters of reference indicate corresponding parts throughout the several views.

30 In bowling alleys it is customary and desirable to illuminate the alleys in the vicinity of the pins by an overhead light, an electric lamp being usually employed. At the present time this lamp is mounted on an overhead 35 or ceiling-suspended pipe immediately above the alleys and this pipe is fixed, making it very difficult to effect the cleaning or resurfacing of the alleys or effect repairs, unless the pipe is either bent or disconnected from 40 its support, which entails considerable time and often results in breakage of the pipe and connections. Furthermore, one of these lamps is individually associated with each 45 alley. In my invention, I aim to eliminate the objections existing in the present lamp mounting by providing a swinging lighting fixture which serves two adjoining alleys and which normally is disposed crosswise thereof, the same being readily shifted parallel to the 50 alleys where it is out of the way to conven-

iently effect repairs to the pin-setting mechanism or for refinishing the bed of the alleys.

Referring now to the drawing, 10 indicates the alley-bed, 11 the gutters, 12 the sub-flooring, and 13 and 14 the leveling strips and blocks, respectively, which are arranged between the sub-flooring and the alley-bed. Disposed lengthwise between the gutters of adjoining alleys is the customary division 55 wall or strip 15 which terminates at its rear 60 end in the side board 16.

Mounted on the division wall 15 forwardly of the side boards 16 is my improved lamp mounting which serves to illuminate the adjoining alleys on either side of the division 65 wall and which may be readily shifted from its normal operative position at right angles to such wall to a position parallel therewith, wherein the lamps are disposed clear of the alleys and substantially in the plane of the 70 division wall to permit cleaning or resurfacing of the alleys as well as other repairs in that locality without interference from the lamps and its supporting structure or mounting. This mounting is preferably constructed 75 as follows:

Disposed crosswise below the division wall 15 and secured to the sub-flooring 12 in the space between adjoining leveling strips is a T-fitting or pipe connection 17 to which is 80 connected a pipe or hollow standard 18 arising therefrom and extending through an opening in the division wall, as seen in Figure 1. Applied to the upper end of this standard is a horizontally swinging lamp-frame 85 consisting of a yoke or Y-fitting 19 from which radiate oppositely extending pipes or conduits 20 which, in the normal position of the device, overhang the adjoining alleys in the manner shown in Figure 1, 90 and which are provided at their outer or free ends with a combination lighting fixture 21 containing electric lamps, not shown, which serve to illuminate the pins on the alley as well as indicate when a foul has been made 95 by the bowler. The numeral 22 indicates a flexible cable containing wires 23 leading to the lamps contained in the lighting fixture 21, this cable extending through the standard 100 18 and the pipe fitting 17, from which it is

directed to the source of current supply. This cable preferably extends transversely beneath the alleys and its wires are connected to the several lamp fixtures associated with the group of alleys.

To permit of readily shifting the lamp-carrying yoke to a position crosswise of or parallel to the alleys 10, I preferably provide a telescopically arranged sleeve or pipe 10 section 24 which may be secured to the upper end of the standard 18 and which projects a suitable distance upwardly therefrom, the lower end of the Y-fitting 19 being loosely fitted over the sleeve so as to be free to turn 15 thereon. For the purpose of holding the Y-fitting in a set position, I provide its lower edge with a tooth or projection 25 which in the crosswise or operative position of the lamps is adapted to interlock with a corresponding notch 26 formed in the upper edge of the standard 18. In the inoperative position of the lamp mounting, wherein the same is disposed parallel to the alleys, the tooth 25 is adapted to engage a recess or notch 27 like- 20 wise formed in the upper edge of the standard 18 at substantially 90 degrees from the companion notch 26.

While manifestly simple and compact in construction, this improved lamp mounting 30 for bowling alleys is easy to install, it can be readily turned to an operative or inoperative position, and it serves to illuminate two adjoining alleys, thereby effectually eliminating the objections encountered in the present mountings employed for illuminating the alleys.

I claim as my invention:—

1. In combination with the sub-flooring and division wall of adjoining bowling alleys, of a tubular base member secured to the sub-flooring beneath said division wall, a standard rising from said base member above the division wall, and a lamp-bearing frame mounted on the upper end of said standard 40 for movement about the axis thereof to assume a position at right angles to the division wall in overhanging relation to the alleys or a position in line with said division wall.

2. The combination with a pair of bowling alleys and the longitudinal division strip between the gutters thereof, of a standard rising from said division strip, a lamp-bearing frame mounted on said standard for horizontally-swinging movement about the axis 50 thereof, said frame including oppositely-extending lamp supports adapted to assume an operative position at right angles to the division strip in overhanging relation to the alleys or an inoperative position in line with the division strip and parallel to the alleys, and complementary means on said standard 55 and said frame for holding the latter against displacement in either of said positions.
